UNITED STATES PATENT OFFICE.

WILLIAM W. WORCESTER, OF CINCINNATI, OHIO.

FENCE STAY OR BRACE.

SPECIFICATION forming part of Letters Patent No. 275,007, dated April 3, 1883.

Application filed February 21, 1883. (No model.)

To all whom it may concern:

Be it known that I, WILLIAM W. WORCESTER, of the city of Cincinnati, in the State of Ohio, have invented a certain new and useful Improvement in a Fence Stay or Brace, of which the following is a full, clear, and exact description, reference being had to the accompanying drawings, forming part of the specification, in which—

10 Figure 1 is a side elevation of my invention detached; Fig. 2, a front elevation of a fence provided with my improvement; and Fig. 3, a vertical transverse section through the fence, with my improvement shown in elevation.

15 My invention relates to an improvement in stays or braces for wire fences; and it consists in the peculiar construction and arrangement of parts hereinafter described, and then pointed out in the claims.

20 In the drawings, A A represent two posts of any suitable shape or material, to which are attached in any manner the wires B, which may be barbed or otherwise, as desired.

C represents a bent or spiral wire, preferably having a coil, c, at one or both ends, as shown more particularly in Fig. 1.

D is a straight wire having one end bent, as shown in Fig. 1; but this bend may be dispensed with.

25 This improvement is applied as follows: The spiral wire is placed in a vertical position against the horizontal wires B and in close contact therewith. The straight wire is then passed through the upper coil, c, of the spiral coil, and down toward and through the lower coil, c, on the sides of the horizontal wires, opposite to those touched by the spiral wires. The bend at the top of said straight wire may hang down over the top horizontal wire, and

may, if preferred, be bent under it to prevent 40 its abstraction by mischievous or evilly-disposed persons; or the wire may be fastened in position in any suitable manner—such, for instance, as bending its lower end. By this arrangement a very cheap and simple, yet strong 45 and substantial, brace or stay is formed that will securely hold and brace the horizontal wires of a fence, making it much stronger and less liable to sag or give way. It can be made and kept in store by hardware-dealers, and 50 readily applied to any fences, either new or those already in position, by any ordinary laborer.

I am aware of the Patents Nos. 70,946, 109,858, 188,816, and 232,250, which show various forms of staying and bracing the wires of fences, &c., and make no claim to anything shown therein.

What I claim as new is—

1. The combination, with the horizontal 60 wires of a fence, of two stiff bracing-wires, one being curved substantially as shown, and the other straight, the two being applied to the fence by the straight wire passing through the bends of the curved wire, substantially as 65 described.

2. The combination, with the horizontal wires of a fence, of two stiff bracing-wires, one bent spirally and coiled at the end and the other passed through the bends of the 7c bent wire to fasten the horizontal wires in the bends of said bent wire, substantially as described.

WM. W. WORCESTER.
